UNITED STATES PATENT OFFICE

119,229

DESIGN FOR A DRESS

Bernard Ringel, New York, N. Y.

Application February 1, 1940, Serial No. 89,906

Term of patent 3½ years

To all whom it may concern:

Be it known that I, Bernard Ringel, a citizen of the United States and a resident of the city of New York, in the county of New York and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress as shown in Fig. 1.

I claim:

The ornamental design for a dress, substantially as shown.

BERNARD RINGEL.
